UNITED STATES PATENT OFFICE.

SIGMUND LEDERER, OF PROVIDENCE, RHODE ISLAND.

BRACELET.

SPECIFICATION forming part of Letters Patent No. 710,105, dated September 30, 1902.

Application filed April 17, 1902. Serial No. 103,289. (No model.)

To all whom it may concern:

Be it known that I, SIGMUND LEDERER, a citizen of the United States, residing at Providence, in the county of Providence and State 5 of Rhode Island, have invented certain new and useful Improvements in Bracelets, of which the following is a specification.

My invention relates to extension or flexible bracelets, and has for its objects the ends customarily sought in this class of manufactures. Certain advantages of structure have already been attained, noticeably in that disclosed in Letters Patent of the United States No. 676,563, heretofore granted me, wherein a double chain with links diagonally related protected an inclosed spring-core. The angular arrangement of links therein not only penetrates the flesh of the wearer but brings such a strain upon the soldered joints of the several links as to result in disjunction under certain circumstances.

It is my aim to overcome the deficiencies above enumerated and secure additional strength, comfort, and beauty by my new structure.

To this end my invention consists in the novel combination and arrangement of parts hereinafter described, and illustrated in the accompanying drawings, wherein—

Figure 1 is a side elevation of my new bracelet; Fig. 2, a top plan view of a section of the same; Fig. 3, a bottom plan view of a similar section; Figs. 4 and 5, detail views of the yoke members; Figs. 6 and 7, similar views 35 of the link members, and Figs. 8 and 9 transverse sectional views of the members, respectively, taken on lines $x-x$ of Fig. 4 and $y-y$ of Fig. 6.

Similar letters of reference indicate similar 40 parts throughout the views.

In detail my bracelet consists of a series of units A and B alternately engaging each other in an endless chain. The unit A is a yoke consisting of a cross-bar a , having 45 fixed to each extremity a slotted ear or ring b substantially at right angles to itself. Depending from the middle of the cross-bar is a ring-guide c . The unit B consists of two rings or links d , lying in the same horizontal 50 plane, having their peripheries joined by solder or otherwise at a common point e . At this junction is soldered to the contiguous

link-surfaces a ring-guide f at right angles and transversely to the joint-links d .

The units A and B are connected alternately thus: The links d of the unit B are inserted into the circular openings or slots of the ears b in the yoke A, the guides of each unit projecting inwardly in diametrically opposite directions. Passing through the guides $c-f$ and forming the core of the bracelet is a spiral spring g . In order to prevent longitudinal movement of the core, it is advantageous to compress the ring-guides f into very close contact with the core-spirals, as shown 65 in Fig. 9.

Having thus described my invention, what I claim as new, and desire to secure by Letters Patent, is—

1. In a bracelet, the combination with yokes comprising a cross-bar and ears extending at right angles therefrom and provided with openings in their ears, of links passing through said openings, and an elastic core longitudinally traversing the bracelet. 70

2. In a bracelet, the combination with yokes comprising a cross-bar and ears extending at right angles therefrom and provided with openings in their ears and inwardly-directed guides, of links passing through said openings, and an elastic core longitudinally traversing the bracelet through said guides. 75

3. In a bracelet, the combination with a series of yokes comprising a cross-bar and ears extending at right angles therefrom and provided with openings in their ears, of a series of links lying in a plane parallel to the cross-bars of the yokes and passing through said openings, and an elastic core engaging said yokes and links. 85

4. In a bracelet, the combination with a series of yokes comprising a cross-bar and ears extending at right angles therefrom and provided with openings in their ears and inwardly-directed guides, of a series of links lying in a plane at right angles to the ears of the yokes, and passing through said openings, inwardly-directed guides upon the links, and an elastic core longitudinally traversing the bracelet through the guides. 95

5. In a bracelet, the combination with a series of yokes comprising a cross-bar and ears extending at right angles therefrom and provided with openings in their ears and in- 100

wardly-directed guides, of a series of links
lying in a plane at right angles to the ears of
the yokes, and passing through said open-
ings, inwardly-directed guides upon the links
5 of lesser diameter than the yoke-guides, and
an elastic core longitudinally traversing the
bracelet through the guides.

In testimony whereof I have affixed my
signature in presence of two witnesses.

SIGMUND LEDERER.
